UNITED STATES PATENT OFFICE.

FRED BENTLEY, OF DETROIT, MICHIGAN.

SPRING WHEEL.

Application filed September 26, 1921. Serial No. 503,243.

To all whom it may concern:

Be it known that I, FRED BENTLEY, a citizen of the United States, residing at Detroit, in the county of Wayne and State of Michigan, have invented new and useful Improvements in Spring Wheels, of which the following is a specification.

This invention relates to improvements in spring wheels and has for an object the provision of a wheel of this character which includes inner and outer concentrically arranged relatively movable rim members of tubular formation, to provide for strength and lightness of construction, together with means for yieldingly holding the members separated and means for preventing relative lateral movement of said members.

The invention further includes removable means for closing the space between said members to exclude dust, dirt and moisture and thus prevent undue wear of the parts and to insure proper functioning of the latter.

With the above and other objects in view, the invention further includes the following novel features and details of construction, to be hereinafter more fully described, illustrated in the accompanying drawings and pointed out in the appended claims.

30 In the drawings:—

Figure 1 is a side elevation of a spring wheel embodying the invention.

Figure 2 is an enlarged section taken transversely through the rim.

35 Figure 3 is a section on the line 3—3 of Figure 2.

Figure 4 is a fragmentary plan view looking at the inner face of the rim.

Figure 5 is a section on the line 5—5 of 40 Figure 3.

Referring in detail to the drawings, wherein like characters of reference denote corresponding parts, the improved wheel which may be either of the disk, artillery, 45 wire spoke or other suitable well known type, includes an inner rim section 10 and an outer rim section 11. These sections are of tubular formation to insure strength and lightness and are arranged one within the 50 other in spaced relation.

Each of these rim sections is provided with spaced opposed pockets 12, herein shown as of rectangular shape. Any number of these pockets may be provided as 55 desired, the number being governed by the use for which the wheel is intended. Lo-

cated within each of the pockets is a coiled spring 13 whose function is to yieldingly hold the rim sections separated so as to provide the desired resiliency in the wheel. 60 The pockets of the inner rim section are each provided with a removable cover plate 14 which is secured in place by means of bolts or screws 15, so that access may be had to the pockets for the purpose of removing 65 or replacing the springs, or for the insertion of proper lubrication. Positioned within each of the pockets and surrounding the springs is a tubular housing 16, whose sides have a sliding engagement with the 70 adjacent walls of the pockets to provide free radial movement of the rim sections, but prevent relative lateral movement and form guides for the rim sections. The tubular housings 16 are connected to their respective springs by means of clips 17 formed by striking up lugs from opposite sides of the housing.

The rim sections 10 and 11 are provided in their outer faces with seats 18 and positioned within these seats are compressible ring members 19, which may be formed of rubber or like material. The rings 19 are held in place by removable rings 20 secured by screws 21. This permits of the removal 80 of the rings 19 and their replacement when necessary. The rings 19 act to exclude dust, dirt or other extraneous matter so as to protect the interior of the rim and at the same time permit of proper relative movement 85 of the sections.

If desired, the rim may be provided with a tread 21 of suitable construction. The tread is preferably formed of rubber or other compressible material and is held in 95 place by means of annular flanges 22 provided on the rim section 11.

The wheel illustrated in the drawings is of the wire spoke type and the spokes 23 are shown as secured to the inner rim section 100 10 in staggered formation.

The invention is susceptible of various changes in its form, proportions and minor details of construction and the right is herein reserved to make such changes as 105 properly fall within the scope of the appended claims.

Having described the invention what is claimed is:—

1. A spring wheel comprising inner and 110 outer concentrically arranged annular tubular members, spaced opposed pockets located

therein, a spring positioned in each pair of said pockets for yieldingly holding the members in spaced relation, and a tubular casing secured to and surrounding each of the 5 springs for sliding engagement with the walls of the pockets and defining guides.

2. A spring wheel comprising inner and outer concentrically arranged annular tubular members, spaced opposed pockets provided therein, a spring positioned in each 10 pair of said pockets for yieldingly holding the members in spaced relation, a tubular casing secured to and surrounding each of

the springs for sliding engagement with the walls of the pockets and defining guides, 15 annular seats provided in the opposite side walls of the tubular members, compressible rings positioned in said seats and spanning the space between the members and retaining rings removably secured within 20 said seats for removably securing the compressible rings in position.

In testimony whereof I affix my signature.

FRED BENTLEY.
